2,345,338

LIQUID DISPENSING APPARATUS

Mark J. Goldberg, Spring Lake, Mich., assignor
to John Wood Manufacturing Company, Inc.,
Philadelphia, Pa., a corporation of Delaware

Application December 9, 1941, Serial No. 422,211

6 Claims. (Cl. 299—77)

My invention relates to liquid dispensing apparatus, particularly adaptable for dispensing gasoline, of the type wherein an extra loop of the dispensing hose is normally retracted and stored within the casing of the apparatus. In gasoline pumps of this type the dispensing hose is of such length that approximately 10 or 11 feet of hose extends outside of the casing and is formed into a loop when the dispensing nozzle is positioned in the nozzle boot near the top 10 of the casing.

In servicing as high as 95% of the automobiles which stop beside the pump for gasoline, a station attendant is able to reach the gasoline tank of the automobile with the length of hose which always extends outside of the casing. However, occasionally an automobile will stop at the service station in such a position with respect to the pump that the gasoline tank of the car cannot be reached by the operator with the length of 15 hose which normally extends beyond the casing. In such event, the operator pulls out a sufficient length of the looped portion of the hose within the pump, to enable him to dispense gasoline from the nozzle at the end of the hose into the gasoline tank.

Two obvious and well known means for storing hose within the casing have been adapted for use in gasoline pumps. Such means are a hose reel on which the extra hose is wound and the arranging of an extra length of hose in a loop within the casing with weight means in the form of a sheave suspended in the bight of such extra loop of hose. In devices of the prior art, the extra loop of hose and the sheave in the bight thereof have been arranged in a well formed within the casing which forms a sort of guide for the hose. In commercial use such structures have proven to be undesirable because it is an inherent characteristic of hose used for gasoline pumps that the hose tends to assume a definite position within the well, which results in the hose rubbing against the side walls of the well. Such contact by the hose with the side walls of the well or housing not only materially increases the amount of effort which the operator must exert to withdraw the hose from the casing, but also detrimentally effects the hose covering.

The principal feature of my invention is the mounting of the sheave, carried in the bight of the extra loop of hose within the casing, on a supporting frame provided with a series of guide rollers, preferably grooved, and the utilization of a pair of the angle bar supporting members of the housing as tracks for the guide rollers to insure an easy up-and-down movement of the sheave in a predetermined path of travel.

My invention includes the various novel features of construction and arrangement herein-after more definitely specified.

Fig. I is an elevation, partly in section, of the front of a commercial type of liquid dispensing apparatus embodying my invention.

Fig. II is a partly sectional side elevation, on a larger scale than Fig. I, of a part of the apparatus shown in Fig. I and showing the chassis frame angle bar members in guiding relation with the rollers of the supporting pulley frame member.

Fig. III is a fragmentary sectional view, taken on the lines III, III in Fig. II, but on a different scale, showing the arrangement of the angle bar supports in guiding relation to the rollers of the pulley supporting frame member.

Referring more particularly to Fig. I, the pump or curbstand, generally indicated by the reference mark 1, includes the rectangular shaped base member 2 on which is rigidly mounted in rectangular arrangement a series of four vertical angle bar chassis frame supports 3. Said angle bars 3 are provided at their lower ends with flanges 4 and are rigidly mounted on said base member 2 by means of a series of bolts 5 which extend through said flanges 4 into screw threaded engagement with said base member 2. Said series of angle bars 3 form a frame support for the sheet metal housing 7 which is also rigidly secured to said base 2, by the bolts 5 extending through the flanged bottom end 8 of said housing 7.

The apparatus shown in Fig. I is of the type disclosed in my copending application Serial No. 302,524 filed November 2, 1939, for improvement in Liquid dispensing apparatus, and includes a bridge frame member 10, of inverted U-shape, which is rigidly mounted on the base member 2 conveniently by a series of bolts 11. The unitary casing 12 is rigidly mounted upon the top of the bridge frame member 10 and contains the pumping unit and the several valves leading to and from the same, and means for separating the lighter fluids from the gasoline and separately discharging them as hereinafter described. Said unitary casing 12 is provided with the head cover 15 on which is rigidly mounted the flow meter 16.

The flow meter 16 shown is of the type including pistons mounted for reciprocation in cylinders and operatively connected with the meter crank shaft 17 which is provided with the coupling 18 at the top thereof for flexible connection with the drive shaft of computing and registering mechanism or other indicating means 20.

Said bridge frame member 10 has rigidly mounted within it the electrical motor 21 provided with the pulley 22 which, by means of the belt 23, is in driving relation with the pulley 24 rigidly mounted on the drive shaft 25 of the pumping unit contained within the unitary housing 12.

60 The liquid supply pipe 27 leads from an under-

ground supply tank, not shown, to said casing 12 with which it is conveniently connected by the coupling 28. Liquid is drawn from the underground tank through the pipe 27 by operation of the pumping unit driven by the electric motor 21, and liquid is forced by the pump through the air separating unit with the solid liquid passing through the meter 18 and the lighter fluids being permitted to flow to the atmosphere through the vent pipe 30. Liquid passes from said meter 18 through the meter discharge outlet 31 into the discharge conduit 33, see-gage 34, and conduit 35 to which is rigidly connected the flexible dispensing hose 36, conveniently by means of the coupling member 37. Said hose 36 is provided at its distal end with the dispensing nozzle 38 having a valve normally spring pressed to closed position, but adapted to be opened by manual operation of the nozzle lever 40.

As best shown in Figs. II and III, a portion of the flexible dispensing hose 36 is arranged within the casing in a loop 42 which has suspended in the bight thereof the sheave 43 provided with the circumferential groove 44 with which the dispensing hose is engaged. Said sheave 43 is mounted with freedom of turning movement on the stud shaft 45 which is rigidly mounted, conveniently by riveting over the end thereof, as at 46, in the rectangular sheave supporting member 47. Said sheave 43 is prevented from becoming displaced axially on said shaft 45 by means of the washer 48 and pin 49 which extends through said stud shaft 45. Said sheave supporting member 47 carries, at each of its four corners, a series of guide rollers 51 each having preferably a circumferential groove 52 forming flanges 53 and 54 which embrace the inner edges of the angle bar chassis frame supporting members 3. Each of said guide rollers 51 is mounted for freedom of turning movement on a stud shaft 56 which is rigidly mounted on said member 47, conveniently by riveting over the end of said stud shaft, as shown at 57. Said guide rollers 51 are prevented from displacement axially on their respective shafts 56 by means of the pin 58. It is obvious that, if desired, said guide rollers may be formed of separate pieces instead of a unitary structure.

As best shown in Figs. II and III, I also find it desirable to provide said member 47 with a pair of guide rollers 60 which are mounted for freedom of turning movement on stud shafts 61 which are respectively rigidly mounted at the two upper corners of the member 47 by riveting over the ends of said shafts 61, as at 62. Said rollers are prevented from axial displacement on their shafts 61 by means of the washers 63 and pins 64.

As best shown in Fig. I, the dispensing hose 36 extends upwardly from around the sheave 43 to the arcuate guide member 70, which is positioned above the computing unit 20 and rigidly fastened at its opposite ends to the angle bar members 3. Said arcuate guide member 70 carries a series of rollers 71 which are conveniently mounted with freedom of turning movement on stud shafts 72 rigidly fastened to said guide member 70. Where the dispensing hose passes through the housing 1, I provide a roller cage 75 comprising a plurality of rollers 76, the axes of some of which are at right angles to others. Said rollers 76 are so arranged to assure that the hose is curved through a sweeping radius and not through a sharp short bend when the hose is drawn out of

the housing by the operator in planes substantially at right angles to Fig. I.

A sufficient length of the hose 36, approximately 10 or 11 feet, continually extends from the opening of the roller cage 75, which amount of hose is sufficient to enable the operator to effect normal servicing operations. When the apparatus 1 is not being used to dispense fluid to an automobile, the hose nozzle 38 is positioned with its outer end within a nozzle boot formed within the upper part of the housing 1. When the apparatus is idle with the nozzle in position in the nozzle boot, that portion of the dispensing hose which is continually outside of the housing is formed into a loop 78, the crest of which is but a few inches off the ground or island level 80.

I have found it convenient to provide a pair of rubber bumpers 82 mounted upon respective angle bars 3 to limit the downward movement of the supporting member 47 carrying the sheave 43. Similar stops 83 may also be provided at their upper portions of the angle bars 3 to limit the extent of upward travel of the supporting member 47.

Operation

Under ordinary circumstances, an automobile will stop in such close proximity to the apparatus 1 that the station attendant, after removing the nozzle 38 from the nozzle boot, will be able to reach the filling opening of the tank of the automobile by utilizing the amount of the hose 36 which normally extends beyond the casing. However, the station attendant occasionally will desire to dispense fluid from the pump to the gasoline tank of an automobile which has stopped at such a distance from the pump 1 that the operator cannot reach the filling opening of the tank of the car with the length of hose which normally extends beyond the casing. In such event, the operator, while holding the nozzle in one hand, pulls on the hose at some point where it extends beyond the casing to withdraw a sufficient amount of the stored hose to enable him to reach the fill cap of the automobile gasoline tank with the nozzle 38. Such pulling motion on the hose causes the sheave 43 to rotate about its stud 45 and moves the member 47 upwardly in Fig. II, thereby causing the rollers 51 to rotate on their respective studs 56 and roll along the edge of the angle bar frame members 3. Such rolling contact between the rollers 51 and tracks formed by the edge of the angle bars 3 enables the operator to pull out the needed extra length of hose with very little effort. Engagement of the plurality of rollers 51 with the guide track angle bars 3 also insures that the sheave 43 and support member 47 are moved in a straight vertical direction when any hose is withdrawn from the casing.

When the operator completes his dispensing of fluid to the tank of the automobile, he merely needs to release his hold on the hose and the weight of the sheave 43 and supporting member 47 causes the hose to be retracted into the casing and to assume its stored position, as shown in Fig. I.

Therefore, I do not desire to limit myself to the precise details of construction and arrangement herein set forth, as it is obvious that various modifications may be made therein without departing from the essential features of my invention, as defined in the appended claims.

I claim:

1. In hose supporting and storing means for a

liquid dispensing apparatus which includes a housing and a long hose with a dispensing nozzle at the distal end thereof and connected at its other end to a liquid supply pipe within the housing, a portion of said hose being arranged in a first loop within said housing and a portion of said hose extending beyond said housing a sufficient length to form a second loop outside said housing when said dispensing nozzle is positioned in a nozzle support at the top of said housing; the combination with a frame support connected to and rigidly supporting said housing; of a sheave in the bight of said first loop of hose within said housing; a sheave supporting member; means for mounting said sheave with freedom of turning movement on said sheave supporting member, with the respective surfaces of said rollers in engagement with a vertical edge of one of said housing frame supports; whereby the edges of said housing frame supports form guide tracks for said rollers to guide and limit the direction of said sheave and sheave supporting member when said sheave is moved by withdrawal or retraction of said looped hose within said housing.

2. In hose supporting and storing means for a liquid dispensing apparatus which includes a housing and a long hose with a dispensing nozzle at the distal end thereof and connected at its other end to a liquid supply pipe within the housing, a portion of said hose being arranged in a first loop within said housing and a portion of said hose extending beyond said housing a sufficient length to form a second loop outside said housing when said dispensing nozzle is positioned in a nozzle support at the top of said housing; the combination with an angle bar frame support connected to and rigidly supporting said housing; of a sheave in the bight of said first loop of hose within said housing; a sheave supporting member; means for mounting said sheave with freedom of turning movement on said sheave supporting member; and a plurality of guide rollers mounted with freedom of turning movement on said sheave supporting member, with the respective surfaces of said rollers in engagement with a vertical edge of one of said angle bar housing frame supports; whereby the edges of said housing angle bar frame supports form guide tracks for said rollers to guide and limit the direction of said sheave and sheave supporting member when said sheave is moved by withdrawal or retraction of said looped hose within said housing.

3. In hose supporting and storing means for a liquid dispensing apparatus which includes a housing and a long hose with a dispensing nozzle at the distal end thereof and connected at its other end to a liquid supply pipe within the housing, a portion of said hose being arranged in a first loop within said housing and a portion of said hose extending beyond said housing a sufficient length to form a second loop outside said housing when said dispensing nozzle is positioned in a nozzle support at the top of said housing; the combination with an angle bar frame support connected to and rigidly supporting said housing; of a sheave in the bight of said first loop of hose within said housing; a sheave supporting member; means for mounting said sheave with freedom of turning movement on said sheave supporting member; and a plurality of flanged guide

rollers mounted with freedom of turning movement on said sheave supporting member, with the respective flange surfaces of said rollers embracing a vertical edge of one of said angle bar housing frame supports; whereby the edges of said housing angle bar frame supports form guide tracks for said flanged rollers to guide and limit the direction of said sheave and sheave supporting member when said sheave is moved by

5 withdrawal or retraction of said looped hose within said housing.

4. In hose supporting and storing means for a liquid dispensing apparatus which includes a housing and a long hose with a dispensing nozzle at the distal end thereof and connected at its other end to a liquid supply pipe within the housing, a portion of said hose being arranged in a first loop within said housing and a portion of said hose extending beyond said housing a sufficient length to form a second loop outside said housing when said dispensing nozzle is positioned in a nozzle support at the top of said housing; the combination with an angle bar frame support connected to and rigidly supporting said housing; of a sheave supporting member; a sheave in the bight of said first loop of hose within the housing, said sheave being mounted with freedom of turning movement on a stud shaft rigidly fixed in said supporting member; and a plurality of guide rollers mounted with freedom of turning movement on said sheave supporting member, with the respective surfaces of said rollers in engagement with a vertical edge surface of one of said angle bar frame supports; whereby the edges of said angle bar frame supports form guide tracks for said rollers to guide and limit the direction of said sheave and sheave supporting member when said sheave is moved by withdrawal or retraction of said looped hose within said housing.

5. In hose supporting and storing means for a liquid dispensing apparatus which includes a housing and a long hose with a dispensing nozzle at the distal end thereof and connected at its other end to a liquid supply pipe within the housing, a portion of said hose being arranged in a first loop within said housing and a portion of said hose extending beyond said housing a sufficient length to form a second loop outside said housing when said dispensing nozzle is positioned in a nozzle support at the top of said housing; the combination with an angle bar frame support connected to and rigidly supporting said housing; of a sheave supporting member; a sheave in the bight of said first loop of hose within the housing, said sheave being mounted with freedom of turning movement on a stud shaft rigidly fixed in said supporting member; and a plurality of flanged guide rollers mounted with freedom of turning movement on said sheave supporting member, with the respective flange surfaces of said rollers embracing a vertical edge surface of one of said angle bar frame supports; whereby the edges of said angle bar frame supports form guide tracks for said rollers to guide and limit the direction of said sheave and sheave supporting member when said sheave is moved by withdrawal or retraction of said looped hose within said housing.

6. A structure as in claim 1, including a plurality of hose guiding rollers mounted with freedom of turning movement on said sheave supporting member for confining said first loop of hose within predetermined limits.

MARK J. GOLDBERG.
